UNITED STATES PATENT OFFICE.

VERNON A. VASSAU, OF WILLOW CITY, NORTH DAKOTA.

MOVABLE PARTITION FOR STOCK-CARS.

1,399,908.

Specification of Letters Patent. Patented Dec. 13, 1921.

Application filed September 8, 1920. Serial No. 408,816.

To all whom it may concern:

Be it known that I, VERNON A. VASSAU, citizen of the United States, residing at Willow City, in the county of Bottineau and State of North Dakota, have invented certain new and useful Improvements in Movable Partitions for Stock-Cars, of which the following is a specification.

This invention relates to a movable partition for stock cars.

The principal object of the invention is to provide a movable partition for stock cars as outlined above so that a car may be divided into two or more compartments to provide for different kinds of stock to be shipped. In shipping stock the railroads require that the different kinds must be separated if shipped in the same car. By using the partition referred to the stock can be properly separated thus saving a great deal of space, particularly when there is not a full car of any one kind of stock.

Various other objects and advantages of my invention will become apparent during the continuance of the following description.

In the drawings:

Figure 1 is a view in cross section of a stock car body, my invention being shown in elevation and in operative relation therewith.

Fig. 2 is a fragmentary view of the partition and the supporting rails therefor.

Fig. 3 is a view in perspective of means to secure the sides of the partition to the sides of the car body.

In the drawings I have shown, for the purpose of illustration a stock car body 10 of substantially conventional form provided with vertical braces 11 and transverse supporting members 12. It is to be understood of course that my invention can be used in connection with car bodies of other construction and that I am not limited to the particular form of body herein shown.

The main or body portion of the partition preferably consists of vertical carrying members 13 connected at their end and intermediate portions by means of transverse braces 14. The carrying members and braces are to be so secured as to provide a rigid frame work. In completing the partition proper I provide a series of baffle rods 15

which have their ends positioned in the upper and lower braces 14 and which extend through the intermediate brace as clearly shown in Figs. 1 and 2. This construction provides a strong and durable partition.

With a view to suspending the partition within the car I first provide horizontal carrying rails 16 which extend longitudinally along the roof of the car body and which may be supported by the transverse brace members 12 thereof. The rails may extend the entire length of the car or only a part thereof as occasion may require.

I also provide an improved hinge to suspend the partition proper from the rail 16 and at the same time allow the partition to be swung so as to permit the stock to pass underneath, if such is required. This hinge consists of a main member 17 and a rail engaging member 18 the rail engaging member having a slot 19 for the reception of the ball and web of the rail. The two hinge sections are pivotally connected as shown at 20. Two of the improved hinges are preferably used, one being positioned at each of the upper and outer ends of the partition and engaged with the respective carrying rail. This arrangement provides means whereby the partition may be moved longitudinally within the car body or swung upon the hinge pivot so as to permit the stock to pass underneath.

I also provide means for retaining the partition in a fixed position within the car body. In carrying this into effect I provide the carrying members 13 with retaining chains 21 of suitable length and eye bolts 22 to receive the normally free end of the chains and the retaining pins 23 in the manner hereinafter described. When it is desired to secure the partition in a stationary position the chains 21 are passed around the vertical braces 11 and the end links pass over the head of the respective eye bolts 22. The retaining pins 23 are then inserted in the head of the eye bolts thus forming a secure connection between the partition and the side wall of the car body.

What is claimed is:

The combination with a housing member provided with vertical braces, spaced from

the sides thereof, of rails positioned beneath the roof thereof, a partition member, hinges connecting said partition member and said rails, said hinges being slideable longitudinally on said rails, means to retain said partition member in a fixed position with respect to said housing member, comprising

means carried by said partition member adapted to encircle said spaced vertical braces and means carried by said partition member to lock said encircling means.

In testimony whereof I affix my signature.

VERNON A. VASSAU.
